PENCIL RACK

Clarence E. Crawford, Flint, Mich., assignor to Living Designs, Grand Blanc, Mich., a partnership

Application May 19, 1948, Serial No. 146,467

Term of patent 14 years

(Cl. D74—17)

To all whom it may concern:

Be it known that I, Clarence E. Crawford, a citizen of the United States, residing at Flint, in the county of Genesee and State of Michigan, have invented a new, original, and ornamental Design for a Pencil Rack, of which the following is a specification, reference being had to the accompanying drawing, forming part thereof.

The showing in broken lines is merely for the purpose of illustration.

I claim:

The ornamental design for a pencil rack, substantially as shown and described.

CLARENCE E. CRAWFORD.
